UNITED STATES PATENT OFFICE.

FRANK KUHN, OF DETROIT, MICHIGAN.

DESIGN FOR A SAD-IRON.

45,671.

Specification for Design.

Patented Apr. 28, 1914.

Application filed April 5, 1913. Serial No. 759,220. Term of patent 14 years.

To all whom it may concern:

Be it known that I, FRANK KUHN, a citizen of the United States of America, residing at Detroit, in the county of Wayne and State of Michigan, have invented a certain new, original, and ornamental Design for Sad-Irons, of which the following is a specification, reference being had therein to the accompanying drawings, forming part thereof.

The figure is a side elevation of a sad iron, showing my new design.

I claim:

The ornamental design for a sad-iron, as shown.

FRANK KUHN.

Witnesses:

JAMES P. BARRY,
DELBERT COLLINS.
